UNITED STATES PATENT OFFICE.

DAVID N. LONG, OF BUFFALO, NEW YORK, ASSIGNOR TO MARY A. LONG,
OF BUFFALO, NEW YORK.

ROADWAY.

SPECIFICATION forming part of Letters Patent No. 779,293, dated January 3, 1905.

Application filed May 23, 1902. Serial No. 108,639.

To all whom it may concern:

Be it known that I, DAVID N. LONG, a citizen of the United States, residing at Buffalo, in the county of Erie and State of New York, have invented a new and useful Roadway, of which the following is a specification.

My invention relates to roadways in which tramways or wheel-tracks of paving-brick or other material are used to carry the vehicle-wheels without tending to the formation of ruts alongside of said tracks. I attain these objects by means illustrated in the accompanying drawings, in which—

Figure 1 is a vertical section of the road; Fig. 2, a top view of one of the tracks; Fig. 3, a vertical section showing some of the means of construction; Fig. 4, a side view of one of the tracks, showing the center crosswise bricks; Fig. 5, a vertical section showing details of construction; Fig. 6, a view of the gage 17 as resting upon crosswise bricks; Fig. 7, an enlarged view of the shield 23.

Similar figures refer to similar parts throughout the several views.

Figure 1 shows a vertical section of a road in which the crosswise paving-bricks 2 or blocks of wood, stone, or other material are bedded in a layer of cement or concrete 5, which may be composed, preferably, of about three or more parts of sand to one of cement and four to six parts of angular stone-screenings, mixed in the usual manner, or a layer of sand may be used just under the brick 2. Lengthwise bricks 3 and 4 or blocks of stone 35 or wood may be interlocked into the crosswise series of blocks 2, about as shown in a top view in Fig. 2. The blocks 3 and 4 may extend beyond the line of the ends of the blocks 2 to engage and catch the wagon-wheels and carry them upon the bricks 2 without tending to form ruts alongside of the tracks. The inner blocks 4, located on the side of the crosswise blocks 2 toward the opposite track, may preferably be of stone and extend above the level 40 of the blocks 2, from about one-half to one inch, to form a flange or guide tending to keep the wagon-wheels on the tracks 2. As the wheels will rub and grind against these stones or blocks 4 to some extent, a stone of high

abrasive quality—like granite, for instance—is 5 preferable to ordinary paving-brick on account of more effectually resisting the wear of the wagon-wheels. The bed of the road between the tracks should be raised above the level of the blocks 4, about as shown in Fig. 1, 55 and may be of paving-stone when placed in old city streets, for instance, or it may be made of any other road material. When these tracks are placed in streets already paved with stone, brick, or asphalt, it is preferable to have their 60 surfaces nearly level in a crosswise direction, so the crown of the street will cause the paving-stones adjacent to the inner side of said tracks to be somewhat higher to form a flange to keep the wheels on the tracks, or the tracks 65 may be depressed slightly below the average tops of the paving-stones on each side, especially when two sets of tracks are used, to meet the same end, as any dirt accumulating on them will be readily washed off between 70 the paving-stones. By this means it may be found practicable in some cases to dispense with the regular jogging of the crosswise bricks and the interlocking of the lengthwise 75 bricks.

The foundation for the concrete base 5 may be of loose stone 6 or of concrete 6^b, as shown in Fig. 1. The outside blocks or stones 3 are preferably placed with their tops level or nearly level with the blocks 2 to enable the 80 wagon-wheels to readily pass upon the tracks 2. The bricks 2 may be placed, preferably, upon a slow-setting concrete or cement 5 before the latter has hardened and their tops leveled by the bricks above the proper level being forced 85 down into the soft cement by means of a straight-edge 18, preferably of hard wood of a thickness to allow it to yield somewhat from a true plane, about as shown in Fig. 4, or if the bricks 2 are nearly uniform in width 90 fine gravel or preferably clean stone-screenings may be substituted for the cement 5, and by having its surface nicely leveled the bricks may be placed on it, and after their tops are leveled by forcing a straight-edge down upon 95 them with a hammer or otherwise the spaces between the stone-screenings and between the bricks composing the series of bricks 2 and

between the bricks 2 and the blocks 3 and 4 | 5 may then be completely filled with cement thinly mixed with water alone, or for the sake of economy the cement may be mixed, preferably, with sand or soil so fine as not to readily settle to the bottom of the mixing-pail, as ordinary coarse sand would do, or the mixing-pail may have a good-sized opening near its bottom provided with a removable 10 stop to allow the grout to run from the bottom of the pail, and thus largely prevent its settling.

Proper spaces between the bricks 2 so as to cause the bricks 3 and 4 to nicely fit into jogs, 15 as shown, may be readily retained by placing between the bricks 2 as they are set a series of four or five gages 17, which may consist of nails secured to blocks adapted to rest on the bricks 2, or they may be in the form of 20 bent wires 17, as shown in Figs. 4 and 6, and adapted to rest upon one brick and allow their ends to extend down between it and the next brick, the ends of the wires being preferably four or five inches apart. By using four or 25 more of these gages the first ones used can then be used again without the bricks getting out of position.

The drain-tiles 7 may be covered with a thin layer of gravel or coarse sand or porous soil, 30 as shown in Fig. 3, to protect them from breaking, when the coarser stone 6 may be placed upon them and rolled or otherwise packed down. A layer of gravel 6^a or stone-screenings may also be placed against the bed 35 of earth 8, as shown in Fig. 3, to make a non-yielding bed for the stones 6 and prevent their protruding parts from settling into the earth 8, by which means a more substantial foundation for the bricks or blocks 2, 3, and 40 4 and the adjacent road is secured. The stones 6 adjacent to and under the bricks 2 may be readily rolled down to a grade below the existing center of the road-bed by running the driving-wheels of an ordinary traction-engine on them, or common wagons properly loaded may be hauled over the stone 6 with good results, especially if the wheels have wide tires. The tiles 7 are preferably placed outside of a perpendicular line from 45 the outside of the blocks 3, or in some cases if placed outside of a perpendicular line from the outside of the blocks 2 the same end may be attained. The object of placing the tiles 7 in this position is that if they become 55 clogged they may be taken up and cleaned out without disturbing the blocks 2 or 3, as the case may be, or the foundation under them. The earth 8 if excavated about as shown in Fig. 3, nearly on a uniform curve or crown, 60 will enable a heavier foundation to be placed where most needed than otherwise would be the case with using the minimum amount of stone, which is an important consideration in sections where stone is scarce. This form 65 of the earth or one slanting to the tiles 7

will also readily carry any water percolating to it to the tiles 7. In some cases a finer sand, stone, or gravel may be used under the center of the road-bed to better advantage than the coarse stone, as the paving-stone 1 | 70 may be bedded directly into it, as shown in Fig. 1. The stone 6 should be of sufficient size to cause air-spaces to remain between them to provide a non-conductor of cold and prevent the frost from penetrating into the 75 earth below the blocks 2, 3, and 4 and heaving them out of their proper places. The foundation-cement 5 may also extend partly or wholly below the side blocks 3 and 4, as shown in dotted lines, or only under the cross-wise blocks 2. In the latter case if any of the blocks 3 or 4 are forced down by the wagon-wheels below their proper position they will not disturb the bricks 2 or the foundation under them and may be readily raised 80 again into place. These wheel-tracks, as shown in Fig. 1, may be placed in old cobblestone or macadam, brick, or asphalt streets by removing narrow trenches of only about enough of the old cobblestone or other street-surface to 85 make room for the blocks 2, 3, and 4 and any foundation and drainage that may be placed beneath them, by which means a smooth and nearly noiseless track can be constructed in old cobble streets, for instance, at little cost 90 and without disturbing much of the street, while a less slippery roadway is thus provided for the horses' feet than can be had in either brick or asphalt pavements.

For city residence-streets and country roads 95 the use of a thin layer of gravel or similar material on each side of the tracks in cases where the soil is not naturally well drained will enable the grass to form a heavy and permanent sod directly up to the tracks if properly 100 fertilized, thus doing away with all dust-forming surfaces except between the wheel-tracks, and this space will likely grow a fine sod as soon as automobiles displace the use of the 105 horse.

As the wheel-tracks take nearly all of the 110 wear and grind of the wheels, blast-furnace slag or other soft or porous substance may be used to special advantage between and adjacent to the tracks, as it will receive but little wear, and consequently will last very well, especially if some hard stone or similar substance is mixed in the surface layer to enable it to better withstand the action of the horses' feet, especially between the tracks, or the 115 spaces between the surface of the stone or other material between and adjacent to the wheel-tracks may be filled with heated tar, pitch, or asphaltum, adhesive clay, or similar substance to prevent raveling, to meet the 120 same end. One advantage of using blast-furnace slag or other porous material in cold climates is that the air-spaces in it will largely prevent the penetration of frost through and below it. This same end may be secured by 125 130

using stone with sufficient air-spaces between the stones located beneath the surface. Where the natural soil or other substance liable to heave by freezing is left between and outside of the wheel-tracks, by placing a layer 5 of such frost-proof or other non-compacting material, like tanbark, sawdust, loose gravel, or stone-screenings, with air-space between them, for instance, between the body 10 of earth and the tracks, as shown in Fig. 5, the heaving of the soil by the action of frost may be prevented from raising and displacing the tracks.

In some cases the cement, concrete, or stone 15 foundations may extend only to the outer ends of the bricks 2, as shown in the left-hand track in Fig. 1, so as to allow the inner edges of the bricks 3 and 4 to securely rest thereon, or in some cases it may be best for this foundation 20 to extend only to the inner ends of the cross-wise bricks 2, as shown in the right-hand track in Fig. 1, so if the lengthwise bricks 3 and 4 are forced down by the action of the wagon-wheels the foundation will not be affected 25 thereby, or the foundation may extend to the outside edges of the bricks 3 and 4, as shown in Fig. 1 in dotted lines, or somewhat beyond, to securely sustain said bricks 3 and 4 and also any stones or other material placed between or next to them. A bed of broken stone 30 or other material extending a few inches beyond the bricks or stones 3 and 4, as shown in Fig. 3, will assist in preventing the formation of ruts next to the bricks 3 and 4, or stones 35 of considerable size may be placed between them and against the ends of the bricks 2 and extend beyond the outside line of the bricks 3 and 4 enough to effectually engage and lift wagon-wheels passing outside of the 40 bricks 3 and 4, as shown in Fig. 2.

The base of cement or concrete or other material 5 may have an even surface or a depression or groove 16 in its center to carry grouting through below the bricks 2, as shown 45 in Fig. 3, to better surround the bricks and penetrate the adjacent material. This groove 50 may be made with the blade of a mortar or other hoe if properly curved and held at the proper angle while being moved over said base, or it may be formed by a projection 10^a on the leveler 10 or in any other suitable manner. A body of fine gravel or stone-screenings with the dust removed may be used for the base 5 and one or more grooves made in 55 such body by laying strips on the foundation 6 or the lower part of the base 5 and filling between said strips with concrete, and after leveling such base such strips may be removed. These grooves will enable grouting 60 poured between the bricks 2 to effectually penetrate nearly or quite to the foundation 6 when the base 5 is of fine stone, and thus firmly cement and hold the bricks 2 to said foundation 6 and base 5. The drain-tile 7 65 may be placed outside of and below the trench

for the foundation, as shown in Fig. 1, in many soils without excavating the soil above them, thereby saving much excavation.

Fig. 3 shows gages 12 secured at the proper distance by irons or other cross-pieces 11, preferably arranged to have their inner edges rest upon the old road-bed left between the trenches dug for the brick tracks. These gages may be used in a number of series arranged so their ends will be held true with each other by 70 dowels or otherwise and should be blocked up true with the line and grade desired for the brick tracks. Where the engineers' stakes are placed one hundred feet apart, a series to 75 reach one hundred or more feet will be of advantage, as they can then be more readily leveled and lined properly between the stakes. If the space between the brick tracks is to be 80 filled with new material, the tops of the gages 12 may be set down nearly on a level with the 85 tracks; otherwise guides 14 may be secured to the outer side of the gages 12, as shown in Fig. 3, and extend down into and preferably to the bottom of the trenches, as shown, to 90 form guides for placing the innermost series of the bricks against to get them into proper line and to prevent the concrete 5 from being forced under the gages 12 and wasted. The outer series of the bricks 2 may be easily lined by placing between them and the removable 95 guides 14 blocks 15 of the proper thickness, usually three-eighths to three-fourths of an inch thick, as shown in Fig. 3, preferably extending the full thickness only so far as to nicely engage the tops of the bricks 2, so they 100 can be readily removed.

The gages 12 should be secured at such a distance from each other that the usual gage of the wagon-wheels will cause the wheel to pass nearly over the average centers of the 105 bricks 2 or a little outside of said centers when the wheels on each track are the same distance from the inside bricks 4. When the traffic is heavy or there is considerable turning out of and into the tracks, in some cases it is better to have the tracks a little wider apart—about an inch wider is a good distance—so when one wheel is in contact with the outside of the brick 4 the other wheel will be well up onto the opposite track—say an inch or more 110 from the outer end of the brick 2; otherwise if the centers of the tracks were the exact crosswise gage of the centers of the wagon-wheels, which vary considerably, when the inside edge of one wheel is against the brick 4 115 the inside of the other wheel would just be even with the outside ends of the inner series of the bricks 2 and tend to form ruts along said ends of said bricks 2. So it is readily seen that in many cases the brick tracks should 120 be far enough apart to at all times carry both wheels well upon the tops of the bricks 2.

A leveler 10, with or without a projection 10^a, may have a rounded lower edge to pack the concrete and be secured to the bottom, 130

preferably, of one end of a movable cross-bar 10^b, which should be of sufficient width to prevent the leveler 10 from readily tipping. The leveler 10 may be made of stiff sheet metal, 5 which may be set or moved at an angle to plow the excess concrete to the outside. The bar 10^b extends across both of the gages 12, so it can readily be moved lengthwise on them and cause the leveler 10 to level the top of the 10 foundation-concrete 5 to the true grade of the brick tracks, when the bricks 2 may be placed thereon, and before the concrete has hardened their tops should be perfectly leveled with the straight-edge 18, as shown in Fig. 5, by forcing those higher than desired down into the 15 soft concrete by pounding the straight-edge 18 and forcing concrete under the ends of those which are too low.

The concrete 5 is preferably made with a 20 slow-setting cement, like Portland, so the bricks can be properly placed and leveled before the cement sets. It should also be composed of about two-thirds or more of stone-screenings, passing through one-half or three-eighths inch mesh, to prevent the bricks from 25 settling after they have been leveled. A thin layer of stone-screenings with the finer stone and dust removed may be used instead of the concrete 5, as the grouting if thin enough will 30 penetrate through it.

The outside lengthwise bricks 3 may be put in place preferably while the guides 14 are still in place to keep the bricks 2 from moving sidewise, when the gages 12 and the guides 35 14 may be removed and the center lengthwise stones or bricks 4 be placed in position, which may be readily done by filling cement below them so as to bring their tops even with the upper side of a short board or block 13, laid 40 upon the bricks 2 of the thickness it is desired to have the bricks 4 raised above the bricks 2, from one and one-half to one inch being the usual distance. When the bricks 2, 3, and 4 are thus properly placed, boards 19 and 19^a, 45 as shown in Fig. 5, may be set against the outer sides of the bricks 3 and 4, extending several inches above said bricks and there secured in a temporary manner. A board 20 may then be placed on the top of the bricks 2 50 and preferably against the bricks 4 to keep the cracks between the bricks clean for grouting, when loose earth 20^a may be filled into the spaces between the bricks 2 and the boards 19 and 19^a to a point a little above the level 55 of the bricks 4 to form side dams for grouting the spaces between the bricks, when the board 20 may be removed and the grout poured on the bricks 2 in the space which has been occupied by the board 20 and swept along to 60 thoroughly fill the cracks and spaces between and below the bricks, after which the earth 21^a and the boards 19 and 19^a may be removed, by which means a better job can be done with less cement than would otherwise be the case. 65 When loose snow is abundant, it may be banked

against the sides of the bricks and the boards 19 and 19^a and earth 20^a between them and the bricks may be dispensed with.

Where there is much turning out and in and the inner brick 4 cannot be had of a very good 70 quality nor be substituted by very hard stone, ordinary hard-burned brick may be made to withstand the side thrust and grind of the wagon-wheels by having end holes 21 made into them before they are baked, preferably in the 75 centers of their ends, as shown in Fig. 5, into which after the bricks are baked the inwardly-turned ends of iron or steel rods 22 may be sprung and secured so the rods 22 will pass over the tops of the bricks 2 when the bricks 80 4 are in their proper places and rest against the upper edges of the bricks 4, as shown in Fig. 5, to take the side wear and grind of the wagon-wheels. If worn out, the bars or rods 22 may readily be replaced by removing the bricks 85 4. The cross-section of the rods 22 may preferably be of round or half-round or oval form. The edges of the bricks 4 may also be protected by bands 23 of iron or steel with their ends bent so as to nicely fit over the ends of 90 said bricks, while wires 24 may be secured in holes through the ends of the bands 23 and pass around the bricks 4, preferably through notches near or in the centers of their corners, when the band 23 may be firmly secured to 95 the bricks 4, as shown in Fig. 7, by means of a wedge 25, preferably of rough iron or a non-decaying wood. By this arrangement the bands 23 may be renewed if worn out without removing the bricks 4. Where suitable 100 brick are scarce or very expensive, very good roads may be made with less brick by placing the crosswise bricks 2 on their sides instead of their edges, as shown in Fig. 5, and for points where the brick have to be shipped 105 long distances, so the freight charges are a considerable item, good pressed brick may be wire-cut into two parts before they are burned, thus making two thin bricks 27 out of one ordinary brick, with one rough side to each, 110 which may be placed down, as shown in Fig. 5, to come in contact with the cement, and thus be securely held in place so its true and smooth upper surface will make an even and substantial track for the wheels. The space 115 between and also to a short distance on the outside of the tracks may be economically paved with hard-burned brick 28, laid flat and thoroughly grouted, preferably with Portland cement, for which purpose brick with well-rounded corners are preferable, which if placed crosswise with considerable space between them—say three-eighths or one-half inch—they will give a good footing for the 120 horses even in icy weather. 125

A cheap and lasting pavement for the horses between the tracks may also be made by placing a layer of stone 1^c, preferably from about two to four inches in diameter, on a layer of sand or fine stone-screenings, as shown in Fig. 3, 130

the surface of which has been brought to the desired form or crown for the space between the tracks. These stones should be nearly of uniform diameter, so they can be quickly placed against each other in a single layer, with a hand-rake, for instance, when their tops may be brought to a uniform surface by rolling or tamping them into the layer of sand, when a thin grout of cement or good clay, preferably mixed with stone-screenings, may fill the spaces between them and also a portion of the layer of sand below and securely hold this layer of stone from raveling by the action of the horses' feet. Where the soil is of a compact nature, it may extend directly to the surface and form a suitable surface for the horses' feet.

Fig. 5 shows the brick tracks placed in an earth road of porous or well-drained soil, in which case the drain-tile and stone foundation may be dispensed with and the base 5 placed immediately upon the soil. When the soil is not naturally well-drained, drain-tile and stone or other ballast should be placed under the tracks, about as shown in Figs. 1 and 3. Ballast of burnt clay may be used in place of stone adjacent to the tracks. On all grades on which the water will freely run the brick tracks may be placed to advantage several inches below the bed of the road, as shown in Fig. 5, even when used in the stone or dirt roads, as by so doing a non-washing channel to quickly carry the surface water off and down the grade will be formed, which will prevent the washing of hillside roads. This will also make the usual water-breaks on hillside roads unnecessary.

In some cases it may be preferable to use wooden blocks set on end between the brick tracks and also in place of the lengthwise bricks on the sides. These can be filled with tar, pitch, or asphaltum or other preservative by placing them endwise upon a pan with a little of the said substance, and by properly heating the same the heat will carry such substance into and through the wood.

Where horizontal facing-stones form a continuous series in streets next to the curbstone, they may be utilized for one of the tracks by depressing the other track below the adjacent surface of the street to form a sufficient guide for the wagon-wheels, or the side bricks 3 and 4 may both be raised above the crosswise bricks 2 to meet the same end. Where cobblestone streets are very rough, it may be found advantageous to use the old cobblestone street for a foundation for the brick tracks by using macadam or other material on the sides and between them to build up to the proper level for the brick tracks.

When screenings or the bases 5 under the brick tracks are cemented by grouting, it may be best to fill the screenings and the lower part of the cracks between the bricks with a

quick-setting cement and the upper part with 65 a slower-setting Portland cement, by which means the filling on the sides of the tracks can be put in place sooner without disturbing the tracks, especially in cold weather, when the cement sets slowly. This method may also be 70 used when the base 5 is of concrete. Where a concrete base is used under the base 5, by using blast-furnace slag in place of stone a firmer base may be secured with much less concrete. 75

If preferred, the boards 19 and 19^a or a bank of earth substituted therefor may be placed directly against the ends of the crosswise bricks 2, and the lengthwise bricks or stones 3 and 4 may be placed after the cementing of 80 the bricks 2 has firmly set, by which means the bricks 2 are less liable to be moved out of place, especially by the placing of the bricks 4, as the bricks 3 may be properly placed without disturbing the bricks 2 before the 85 frames 12 are removed. The boards 19 and 19^a may have thin or sharp lower edges to prevent the grouting from running under them, as is apt to be the case when the lower edges are thick, as in such case it is difficult to 90 properly pack the soil or other material 20 under them without leaving considerable spaces into which the grout will settle. The outside bricks 3 may also be laid flat, and thus present a greater jog to engage the wagon-wheels and 95 carry them upon the bricks 2 without forming ruts.

When the top layer of stones 1^a have been properly compacted, stone-screenings with the dust removed may be filled into the spaces between them, when the whole may be well grouted with a tenacious clay that will harden well when dry, thinned with water, or if the weather is rainy the clay may be pulverized and filled into all spaces between the stones 1^a. 100 In some cases the filling with stone-screenings may be dispensed with. This treatment with clay may be used on any stone or macadam roads, as the clay will become hardened in dry weather and firmly hold the stones in place, 105 and thus prevent raveling, while if any stones are slightly loosened from the clay the first rain will again cement them together. Care should be taken that the stones 1^a are firmly settled before the clay is applied, for if any 110 material amount of clay should get under them it would likely cause them to settle in wet weather. The leveler 10 may also be used to level the concrete 6^b by extending it about an inch downward to leave space for 115 the base 5, or the concrete 6^b may be leveled fairly well by bringing it up to a line stretched on one or both sides thereof.

What I claim as my invention, and desire to secure by Letters Patent, is—

1. In a roadway, a wheel-track consisting of transverse paving-blocks, and having an upward projection or ridge at its inner side and

- a sloping surface at its outer side which is substantially flush with the track adjacent thereto, substantially as set forth.
2. A wheel way or track, composed of transverse tread-blocks, and blocks projecting at intervals from the side or sides of the way, substantially as set forth.
3. A wheelway, composed of tread-blocks and longitudinal blocks arranged along the side of the tread-blocks and interlocking therewith, substantially as set forth.
4. A wheelway of tread-blocks having adjacent blocks thereof offset laterally from side to side of the way for producing alternate recesses and projections along the sides thereof, substantially as set forth.
5. A wheelway composed of tread-blocks and upward projections arranged at intervals along the side of the tread-blocks, substantially as set forth.
6. In a roadway two wagon-wheel tracks, a row of projections arranged at intervals along the inner side of each track and extending above the level thereof, and a row of lateral projections extending along the outer side of each track, substantially as set forth.
7. In a wagon-way two tracks of tread bricks or blocks, interlocking lengthwise blocks extending above the main surface of said tracks on the sides thereof toward the opposite track.
8. In a wagon-way two tracks of tread bricks or blocks interlocking lengthwise blocks extending above the main surface of said tracks on the sides thereof toward the opposite track and projecting beyond the ends of said tread-blocks, substantially as shown and described.
9. In a roadway, brick wheel-tracks having upward projections at intervals at their inner sides, and sloping surfaces at their outer sides substantially flush with said tracks, substantially as set forth.
10. A wheelway composed of main or tread blocks, and side blocks arranged at intervals along the tread of said wheelway, substantially as set forth.
11. In a wagon-way, brick tracks for the wheels having irregular projections from the outer sides thereof with surfaces practically even with the tread of said tracks, substantially as described.
12. In a wagon-way, brick tracks for the wheels having irregular projections from the outer sides thereof with surfaces even with said tracks and raised projections from the inner sides thereof, substantially as set forth.
13. A brick wheelway of tread-blocks having adjacent blocks thereof offset laterally from side to side, substantially as set forth.
14. A wheel-track comprising tread-bricks placed on their sides and projections arranged at intervals along the sides of the tread of said track, as set forth.
15. Wagon-wheel tracks of jogging tread blocks or bricks, side bricks placed in said jogs, those on the outside of said track laid flat to present a greater jog or projection to engage wagon-wheels and carry them on said tracks.
16. The combination of a wheel-track of tread-blocks having a cement foundation extending beyond the ends of said blocks and partly below side blocks or bricks interlocking into said tread-blocks, substantially as described. 70
17. A wheel-track of tread-blocks having a cement foundation extending beyond the ends of said blocks and below side blocks interlocking into said tread-blocks, substantially as set forth. 75
18. In combination with wheel-tracks of jogging paving brick or blocks, a bed of broken stone or similar material adjacent to the tread of said tracks and nearly level with the outsides of said tracks to prevent the formation of ruts, substantially as described. 80
19. In combination with a track of tread-blocks, lengthwise side bricks or blocks interlocking in the sides thereof, and stone of sufficient size adjacent to said tread-blocks to extend beyond the outside line of the side 90 bricks to prevent the formation of ruts along the side bricks, substantially as specified.
20. A wheel-track of tread blocks or bricks placed on their sides and interlocking side brick placed on their edges, substantially as 95 set forth.
21. Wagon-wheel tracks having upward projections at intervals from their inner sides, the distance between the centers of said tracks being greater than the prevailing width or gage 100 between the wheels of the vehicles using said tracks so that when one wagon-wheel is against one of the said projections the opposite wheel will rest securely upon the opposite track even if its gage is unusually wide or its wheels 105 are wobbling, substantially as set forth.
22. Brick wagon-wheel tracks having upward projections from their inner sides and nearly level outward projections from their outer sides, the distance between the centers 110 of said tracks being nearly equal to the usual gage of wagon-wheels, substantially as described.
23. In a wagon-way, tracks for the wheels having projections from the outer sides thereof with surfaces even with the said tracks and raised projections from the inner sides thereof, a road-bed between said tracks at substantially a higher level than said inner projections, substantially as specified. 115
24. A brick wagon-track road having projections at intervals above the surface of the wheel-tracks and touching the tread portion thereof on the inner sides thereof, a road-bed between said tracks having a surface above the 120 surface of said tracks, substantially as set forth.
25. A wheel-track the lower part of the spaces between the blocks thereof being partly filled with an inferior quick-setting grout to 130

enable the sides to be promptly finished without destroying the uniformity of said track, substantially as described.

26. A wheel-track the lower part of the space between the blocks thereof being partly filled with inferior quick-setting grout, to enable the sides to be promptly finished without destroying the line of grade of said track, the upper portion of said spaces being filled 10 with a superior slower-setting cement, as set forth.

27. Wheel-tracks of jogging paving-bricks, grouting placed between said bricks, side bricks placed in side jogs in said paving-bricks 15 after said grouting has hardened, as set forth.

28. Wheel-tracks of jogging paving-bricks, grouting placed between said bricks, side bricks placed in said jogs in said paving-bricks, the side bricks on the outside of said 20 tracks laid flat to prevent a greater jog or projection to engage wagon-wheels and carry them on said tracks.

29. The combination of a wheel-track placed in a street having a series of horizontal facing-stone, in such a manner that said stone 25 will form one track for the wagon-wheels, substantially as described.

30. The combination in a street having a nearly even and horizontal surface next to the 30 curb-like facing-stone, of a depressed wheel-track located at such a distance as to cause one of the wagon-wheels to travel upon said surface, substantially as set forth.

31. In combination with a wagon-way having tracks of tread-blocks a foundation of earth on a grade to points below the level and adjacent to the tracks of said way, fine stone 35 or screenings on said foundation between said tracks, and paving or surface stone bedded in 40 said screenings and secured from raveling by an adhesive clay, substantially as set forth.

32. In a wheelway, tread blocks or bricks placed upon a foundation having a groove or 45 grooves below said bricks to better carry a grouting substance into all spaces between said bricks, substantially as set forth.

33. In a wheelway, tread blocks or bricks placed upon a foundation having a groove or 50 grooves below said bricks to better carry a grouting substance into all spaces between and below said bricks, said groove being formed by a hoe or leveler, substantially as set forth.

34. In a wheelway, tread blocks or bricks 55 placed upon a foundation having a groove or grooves below said bricks to better carry a grouting substance into all spaces between and below said bricks, said foundation being of fine gravel or clean stone-screenings, substantially as specified.

35. Wagon-tracks, of tread-blocks having upwardly-projecting lengthwise bricks interlocking on their inner sides, the outer sides 60 of which are protected by metal bars extend-

ing over the ends of some of said crosswise bricks, substantially as specified.

36. Wagon-tracks of tread blocks or bricks having upwardly-projecting lengthwise bricks interlocking on their inner sides, the outer sides of which are protected by metal bars 65 extending over the ends of some of said tread-blocks, and secured to said lengthwise bricks, substantially as described.

37. Wagon-tracks of tread blocks or bricks having upwardly-projecting lengthwise bricks 75 interlocking on their inner sides, the outer sides of which are protected by metal bars extending over the ends of some of said tread-blocks, and secured by wires engaging in holes in the 80 ends of said bars, and passing partly around said lengthwise bricks, substantially as set forth.

38. Wagon-tracks of tread blocks or bricks having upwardly-projecting lengthwise bricks interlocking on their inner sides, the outer 85 sides of which are protected by metal bars extending over a portion of some of said tread-blocks and passing around said lengthwise bricks, and through notches in the inner corners thereof, substantially as specified. 90

39. Wagon-tracks of tread blocks or bricks having upwardly-projecting lengthwise bricks interlocking on their inner sides, the outer 95 sides of which are protected by metal bars extending over some of said tread-blocks and secured by wires engaging in holes in the ends of said bars and passing around said lengthwise bricks and through notches in the inner corners thereof by means of wedges or similar means, forced between said wires and the 100 inner sides of said bricks, substantially as described.

40. Wagon-tracks, the treads of which consist of a row of transverse paving-bricks placed in narrow trenches formed in paved 105 or stone streets and leaving nearly all of the old street-surface undisturbed, substantially as described.

41. Narrow wheel-tracks consisting of a row 110 of even-surfaced paving-bricks placed in old paved streets and adjacent to the old street-surface the surface of said blocks being located below the average of the said street-surface adjacent thereto.

42. Narrow wheel-tracks consisting of a row 115 of even-surfaced paving blocks or bricks placed in old streets and adjacent to the old street-surface on grades adapted to freely carry water, said tracks being located below the adjacent surface of said streets to convey 120 the surface water to the lowest points thereof, substantially as set forth.

43. A wheelway composed of a row of tread-blocks and blocks projecting at intervals from the side or sides of the said tread-blocks and extending to the tread-surface of said tracks, substantially as set forth. 125

44. A wagon-track, the tread of which con-

sists of a row of bricks placed in old stone or paved streets so the crown of the street will cause the adjacent old street-surface on the inner side of said tracks to be somewhat higher than said tracks, substantially as set forth.

45. Wheel-tracks of paving bricks or blocks, the treads of which have alternating depressions in and projections from the sides thereof.

46. The process of constructing brick wagon - wheel tracks, consisting of placing tread-bricks alternately in line and in jogs from such line and upon a cement base while the latter is still in a soft condition, substantially as set forth.

47. The process of constructing brick wagon - wheel tracks, consisting of placing tread-bricks alternately in line and in jogs from such line and upon a cement base, then bringing the top surfaces of said bricks to an even and smooth plane, substantially as set forth.

48. The process of constructing wagon-wheel tracks, consisting of placing tread-bricks alternately in line and in jogs from such line and upon a cement base, then bringing the top surfaces of said bricks to an even or smooth plane and grouting the spaces between said bricks.

49. The process of constructing brick wagon - wheel tracks, consisting of placing tread-bricks alternately in line and in jogs from such line and upon a cement base, then bringing the top surfaces of said bricks to an even or smooth plane and inserting side brick in said jogs, substantially as set forth.

50. The process of constructing brick wagon - wheel tracks, consisting of placing tread-bricks alternately in line and in jogs from such line and upon a cement base, then bringing the top surfaces of said bricks to an even or smooth plane and inserting side brick in said jogs and grouting the spaces between said tread-bricks, substantially as set forth.

51. The process of constructing brick wagon - wheel tracks, consisting of placing tread-bricks alternately in line and in jogs from such line and upon a cement base, then bringing the top surfaces of said bricks to an even or smooth plane and inserting side brick in said jogs and grouting the spaces between said

treads and said side bricks, substantially as set forth.

52. The process of constructing brick wagon - wheel tracks, consisting of placing tread-bricks alternately in line and in jogs from such line and upon a cement base leveled true with the grade of the road, substantially as set forth.

53. The process of constructing brick wagon - wheel tracks, consisting of placing bricks for a tread upon a hardening cement, banking the sides of said treads to prevent the wasting of grouting material and then grouting the spaces between said bricks, substantially as set forth.

54. The process of constructing brick wagon - wheel tracks, consisting of placing tread-bricks alternately in line and in jogs from such line and upon a cement base, placing bricks in said jogs, banking the sides of said tracks and said side bricks and grouting the spaces between said tread-bricks and also the spaces between said treads and side bricks with a grout of hardening cement, substantially as set forth.

55. The process of constructing brick wagon - wheel tracks, consisting of placing tread-bricks with nearly parallel surfaces alternately in line and in jogs from such line and upon a cement base, placing bricks in said jogs, banking the sides of said tracks and said side bricks and grouting the spaces between said tread-bricks and also the spaces between said treads and said side bricks with a grout of hardening cement, substantially as set forth.

56. The process of constructing brick wagon - wheel tracks, consisting of placing tread-bricks alternately in line and in jogs from such line and upon a cement base, placing side brick in the jogs on the inside of said tread-bricks and upon a cement base with their tops above the level of said tread-bricks, and grouting the spaces between them, substantially as set forth.

In testimony whereof I have signed my name to this specification in the presence of two subscribing witnesses.

DAVID N. LONG.
